Primary Examiner — Susan Bennett Hattan*Assistant Examiner* — Leanne Was*(74) Attorney, Agent, or Firm* — Thomas | Horstemeyer, LLP(57) CLAIM

I claim the ornamental design for a band for decorative glassware, as shown and described.

DESCRIPTION

FIG. 1 is a perspective view showing a band for decorative glassware;

FIG. 2 is a side view of the band for decorative glassware of FIG. 1; and,

FIG. 3 is a top plan view of the band for decorative glassware of FIG. 1.

The broken line showing of an image depicted in FIGS. 1 and 2 is for the purpose of illustrating environmental structure and forms no part of the claimed design.

1 Claim, 1 Drawing SheetFIG. 1
